VENDING MACHINE FOR FROZEN CONFECTION

George W. Kalbitzer, Jr., Los Angeles, Calif., assignor, by mesne assignments, to J. P. Seeburg Corporation, Chicago, Ill., a corporation of Illinois

Application November 18, 1935, Serial No. 50,267

3 Claims. (Cl. 312—36)

My invention relates generally to vending machines, and more particularly to coin controlled vendors for dispensing frozen or chilled commodities such as ice cream confections.

5 An object of my invention is to provide a novel vendor of this character wherein solid carbon dioxide or "dry ice" is utilized to maintain the commodity at the proper temperature.

An object is to provide a novel vendor for 10 chilled commodities which provides a particularly efficient insulation around the commodity stored therein and minimizes the infiltration of heat during the vending operation.

An object is to provide a novel vendor of this 15 character which incorporates a novel vending or dispensing device which, although disposed at the bottom of the storage compartment forms a particularly efficient insulation or seal against outside heat.

20 Another object is to provide a novel dispensing device for vending machines of this character whereby packages are sequentially dispensed from several stacks, said device independently sealing the several stacks in such a manner that the insulation or seal for the idle stack or stacks is not disturbed during vending from the other stack.

Another object is to provide a novel dispensing 25 device for vending machines of this character wherein loss of refrigeration during the vending operation is reduced to a minimum.

30 Another object is to provide in a dispensing device, a novel storage chamber whereby the packages contained therein are spaced from the side walls to facilitate circulation of chilled air there-around.

35 A still further object is to provide a novel vendor of this class which is particularly easy to refill with packages or articles to be dispensed as well as with the refrigerant.

40 A still further object is to provide a novel vendor of this class which incorporates a particularly simple, yet effective means of maintaining a temperature difference between the refrigerant and the packages to be dispensed.

45 Other objects, advantages and features of invention may appear from the accompanying drawings, the subjoined detail description, and the appended claims.

The accompanying drawings illustrate the invention in the form I at present deem preferable.

50 Figure 1 is a front elevational view of my vendor, indicating generally by dotted lines the arrangement of the storage chamber and vending gate and the connection of the vending gate to a coin control apparatus associated therewith.

55 Fig. 2 is a transverse sectional view thereof on line 2—2, Fig. 1 showing the vending gate and coin control mechanism in plan.

60 Fig. 3 is a longitudinal sectional view thereof

on line 3—3, Fig. 1 showing several packages in position within one of the storage compartments.

Fig. 4 is another transverse sectional view thereof on line 4—4, Fig. 3.

Fig. 5 is an enlarged fragmentary sectional view on line 5—5, Fig. 2 illustrating particularly the sealing means provided around the vending gate which is partially broken away to show in elevation the sealing means at the end thereof.

Fig. 6 is another enlarged fragmentary sectional view on line 6—6, Fig. 5, showing particularly in cross-section, the end sealing means for the vending gate.

Fig. 7 is a fragmentary sectional view on line 7—7, Fig. 4, illustrating particularly the driving connection between the coin control mechanism and the vending gate.

My vendor comprises an outer shell 1, a centrally disposed inner shell or storage chamber 2, below which is a vending gate 3. Around the 20 vending gate and inner shell and encased by the outer shell 1 is a filler of any suitable insulating material 4.

The outer shell 1 is preferably formed of any suitable material, and may be of any suitable 25 contour, but is shown rectangular in plan and includes vertical side walls 5 and a bottom wall 6. The top of the outer shell is preferably open and adapted to be closed by a cover 7. The inner shell 2, which likewise may be of any suitable 30 contour, but is shown rectangular in plan, is centered in the outer shell 1 and is also preferably formed of sheet material. The inner shell is open at its top and bottom and extends to the top of the insulation material 4 provided between the two shells 1 and 2. The cover 7 is provided 35 with a block of insulation 8 and a gasket 9 which covers and seals the upper end of the inner chamber 2 when the cover is in position.

The inner shell 2 is divided into two or more 40 compartments 10 by a vertically disposed partition 11 traversing the shorter horizontal axis of the inner shell and is preferably formed of copper or other good conducting material. Each compartment 10 conforms in cross-section to 45 but is larger than the package, designated P, that it contains and which the device is to dispense. The walls of each compartment, including the dividing partition 11, are provided with vertically extending ribs 12 which space the 50 packages P in centered relation with the compartments 10, and provide circulation areas around the articles to be dispensed as best shown in Figs. 3 and 4.

Below the inner shell 2, the insulation material 4 defines a cylindrical gate chamber 13 extending horizontally across the several chambers or compartments 10 and includes a port 14 common thereto. Below the gate chamber 13 a discharge chute 15 is defined forming an aper- 55

ture in the gate chamber 13 coextensive with and opposite the port 14 which coincides with the lower area of the compartments 10. The chute 15 slopes downwardly and forwardly to the forward wall of the shell 1 that is provided with an aperture 16 registering with the chute and an upstanding ledge or flange 16' is provided at the lower and forward edge of the aperture 16 to prevent the articles being dispensed from accidentally falling out of the device.

10 The vending gate 3 fits the gate chamber 13. Said vending gate comprises a cylindrical shell 17 closed at its ends and provided with package receiving pockets 18, one below and coinciding with each compartment 10. In the construction disclosed, two compartments are provided; hence, the vending gate 3 also has two pockets and these are arranged diametrically opposite each other, so that the vending gate alternately 15 discharges packages from the compartments 10. The cylindrical shell 17 of the vending gate 3 is preferably of a hard material such as hard rubber or bakelite and the interior of the vending gate is preferably filled with any suitable insulation material 19.

20 The vending gate 3 is mounted on an axially disposed shaft 20 which is journaled in the ends of the gate chamber 13. The shaft extends from the gate chamber 13 into a recess 21 formed in the insulating material 4 adjacent one side of the shell 1 and a ratchet wheel 22 having two teeth is fixed to shaft 20 within recess 21.

25 The shaft 20 journals a cogwheel 23 which carries a pair of spring depressed dogs or pawls 24 adapted to engage the teeth of the ratchet wheel 22 when the cogwheel is rotated in one direction and to ride thereover when the cogwheel is rotated in the opposite directions. The cogwheel 23 is driven by a rack 25 which in turn is connected to and operated by any suitable coin control mechanism 26.

30 In order to provide an adequate seal between the vending gate 3 and gate chamber 13, the arcuate walls of said chamber between the port 14 and discharge chute 15 are lined with sealing elements 27 as shown best in Fig. 5. Each sealing element comprises a flexible and resilient base portion 27' provided with horizontally extending ribs 28 which extend axially along and bear against the periphery of the vending gate 3 and 35 form therewith a series of dead air spaces 28'.

35 Each end wall of the gate chamber 13 is also provided, as shown in Fig. 6, with a sealing plate 29 of flexible and resilient material having a base portion 29' and ribs 30 extending therefrom 40 which yieldably engage the ends of the vending gate 3 and form therewith dead air spaces 30'.

45 The spacing ribs 12 of the compartments, as well as the partition 11 therebetween do not extend to the upper end of the inner shell but stop a short distance therefrom and form supports for a receptacle 32 which is preferably formed of sheet material and preferably open at its upper end. The bottom of the receptacle 32 is adapted to receive one or more layers or 50 sheets of insulating material 33, such as paper, and is filled with a refrigerant, such as "dry ice" or other sublimable substances 34. The insulating material 33 tends to maintain a temperature difference between the interior of the receptacle 55 32 and the compartment below so that the packages carried therein are not subjected to the extreme low temperature of the refrigerant. By

varying the thickness or number of sheets comprising the insulation material 33 this temperature difference may be readily controlled.

60 Operation of my vendor for frozen commodities is as follows: Upon placing an appropriate stack of articles to be dispensed in the compartments 10, the cover is positioned and may be securely locked thereon against removal by unauthorized persons. Whereupon by placing a coin in the coin controlled mechanism, and operating the same, the rack 25, through the cogwheel 23, dogs 24 and ratchet wheel 22, causes the vending gate 3 to be rotated a half turn and move one of the pockets 18 from the package receiving position shown by solid lines in Fig. 3 to the package discharging position shown by dotted lines in Fig. 3. Simultaneously, the pocket associated with the other compartment 10 is caused to move from the dotted to the solid line position and receive a package ready for 65 delivery in response to the next operation of the vending gate.

70 It should be noted that practically no cold air or refrigerant can drain from the compartment from which a package is being discharged; while the insulation of the other compartment is undisturbed. This economizes the use of a refrigerant and maintains the refrigeration efficiency thereof at a maximum as the sealing means around the periphery and ends of the vending 75 gate 3 resiliently engage such gate 3 by contact of the ribs 28 and 30 therewith, and the dead air spaces 28' and 30' tend to prevent escape of cold air or inlet of warm air to the compartments 10. Also by rotating the vending gate 3 in one 80 direction and delivering articles alternately from compartments 10 I reduce to a minimum the escape of cold air from my vending machine.

I claim:

1. In a vendor; a package storage chamber 40 arranged to receive a stack of packages; a cylindrical gate chamber therebelow; a discharge chute below the gate chamber, there being ports connecting the gate chamber with the storage chamber and discharge chute; a cylindrical vending gate revolvably mounted in said gate chamber; and means lining the walls of the gate chamber and including a plurality of yieldable ribs defining therebetween dead air spaces, and said ribs being engageable with said vending 45 gate.

2. In a vendor; a package storage chamber arranged to receive a stock of packages; a cylindrical gate chamber therebelow; a discharge chute below the gate chamber, there being ports connecting the gate chamber with the storage chamber and discharge chute; a cylindrical vending gate revolvably mounted in said gate chamber; means lining the walls of the gate chamber and including a plurality of yieldable ribs defining therebetween dead air spaces, and said ribs being engageable with said vending 55 gate; and a blanket of insulation material encompassing the storage chamber, gate chamber and discharge chute.

3. In a vending machine, a vending gate to dispense articles; and means associated with said vending gate to provide a plurality of dead air spaces around said gate; said means comprising a flexible base member and a plurality of flexible ribs extending therefrom into contact with 60 said gate.

GEORGE W. KALBITZER, JR.
